UNITED STATES PATENT OFFICE.

ISAAC HUDSON SAPP, OF PAPÉTI, TAHITI, ASSIGNOR OF ONE-HALF TO
WILLIAM T. STUART, OF OAKLAND, CALIFORNIA.

MUSICAL INSTRUMENT.

SPECIFICATION forming part of Letters Patent No. 635,192, dated October 17, 1899.

Application filed May 25, 1899. Serial No. 718,195. (No model.)

To all whom it may concern:

Be it known that I, ISAAC HUDSON SAPP, a citizen of the United States, residing at Papéti, Island of Tahiti, Society Islands, in the 5 South Pacific Ocean, have invented a new and useful Musical Instrument, of which the following is a specification.

This invention relates to musical instruments, and more especially to that class there- 10 of having stretchable heads—such as drums, banjos, and other devices of this character; and the invention includes, broadly, a musical instrument having a stretchable head in combination with an expansile head tension- 15 ing or tightening tube, and for the purpose of illustrating the peculiar construction and manifold advantages of the same I have represented and will hereinafter describe it in connection with a drum.

With these ends in view the invention consists in the novel combination of elements 20 and in the construction and arrangement of parts which will be hereinafter fully described and claimed.

To enable others to understand the invention, I have illustrated the preferred embodiment thereof in the accompanying drawings, forming a part of this specification, and in which—

Figure 1 is a perspective view of a drum 30 provided with a head-tightening device constructed in accordance with my invention and parts being broken away to more clearly illustrate certain features of the invention.

Fig. 2 is a detail in plan view of an expansile tension-regulating tube. Fig. 3 is a trans- 35 verse section of the drum. Figs. 4, 5, 6, and 7 are sectional details hereinafter more particularly described and showing, respectively, modified forms of tension-regulating devices.

Like characters denote like and corresponding parts in each of the several figures of the drawings.

As hereinbefore set forth, my invention is 45 applicable to any of the musical instruments including stretchable heads, whether they be provided with one or more of the latter, and it is illustrated in the drawings in connection with a drum.

The drum represented includes in its construction a body or shell A, provided with the

upper and lower heads B and C, respectively, and the drum-body has near its heads the circumferential annular grooves 2 and 3, respectively, as illustrated in Fig. 1, for the 55 purpose of receiving the expansile head-tensioning tubes hereinafter more particularly described. The tension-adjusting tubes are, designated by 4 and 5, respectively, and are 60 preferably made of rubber, although it is evident that they may be made of rawhide, leather, or any flexible material that will contain an expanding fluid. Any fluid may be employed for expanding the tube; but I provide means for effecting the introduction of 65 air into the same for the purpose of securing the peculiar result, and thereby insuring lightness when the heads are taut or stretched.

The annular grooves 2 and 3 form seats for receiving the tubes 4 and 5, respectively, the 70 latter being preferably made continuous so as to insure the even tightening of the heads.

The heads B and C prior to their introduction are soaked in water until soft and pliable and are then laid across the ends of the body 75 or shell A and the projecting portions pulled toward and across the annular grooves 2 and 3, respectively, and consequently over the annular air-tubes 4 and 5. The margins of the heads are then fastened in the narrow annular grooves 6 and 7 by means of the split 80 rings 8 and 9 or equivalent means, the ends of which are provided with lugs, as 10 and 12, respectively, to receive the adjusting-screws 13 and 14, by turning which the diameter of 85 the split rings can be decreased, thereby to firmly hold the same, and consequently the two heads, in place. It will be understood that the tension-regulating tubes 4 and 5 are disposed within the grooves 2 and 3, respectively, at points between the edges of the drum and the places at which the two heads are secured by the split rings 8 and 9 and that 90 said tubes are located between the heads and the body of the drum, whereby when air is pumped into said tubes the latter will be expanded and will thereby force that part of the heads lying over the grooves radially outward, so as to effect the tightening of said heads.

By seating the two tubes in the annular grooves the walls of the grooves serve to limit 100 the sidewise movement of the tubes when air

is forced into the latter, and as the tubes are located between the heads and the body of the drum these two parts serve to prevent bursting of the tubes.

5 Each of the tubes is provided with an air-supply pipe designated, respectively, by 15 and 16, extending inward therefrom through the body of the drum and then downward and then outward and again through the body 10 of the drum, it being understood that each of these tubes extends through the drum, but does not pass through the heads thereof, as in case openings or holes were formed in the heads to receive the tubes the heads would 15 be materially weakened. The air-supply pipes, which extend transversely from and communicate, respectively, with the tension-regulating tubes 4 and 5, are screw-threaded at their outer ends to receive the removable 20 caps 17 and 18, which may be detached for the purpose of coupling an air-pump of suitable construction to either of the pipes, and each of the latter is provided with a valve (designated, respectively, by 19 and 20) of the 25 tapered type adapted to fit against correspondingly-shaped seats at the ends of the two pipes where they project outside of the drum.

Drum-heads before using should be tightened up, and this operation can be readily 30 effected by removing the caps 17 and 18 and successively connecting an air-pump to the projecting ends of the air-pipes 15 and 16, so as to supply the communicating endless inflatable tubes 4 and 5 with air for the purpose 35 of tightening the heads. When the drum is not in use, the heads should be let down or loosened, and this can be quickly and easily accomplished by removing the caps 17 and 18 and forcing the tapered valves 19 and 20 away 40 from their seats to permit the escape of air from the tension-tubes 4 and 5 and the consequent deflation of the latter.

The hoops or rings 21 and 22, usually of wood, surround the opposite ends of the body 45 or shell A and the overhanging portions of the heads B and C and are connected by one or more rods, as 23, the latter being conveniently fastened to the said body or shell near the middle of the latter; but it is to be distinctly understood that these hoops or rings 50 and rod or rods perform no part of the head-tightening operation, they simply being employed for convenience in carrying the instrument and to protect the edges of the 55 heads from injury at the places where the heads come in contact with the edges of the drum-body.

It is to be distinctly understood that the invention is not in any manner limited to the 60 hereinbefore-described construction, for I have illustrated and will hereinafter describe certain modified forms. It is obvious also that a single tube could be employed for tightening two heads.

65 In Fig. 4 the inflatable tubes 24 and 25 are of slightly-different shape and are adapted to fit against the plain surface of the body or

shell A and between the outwardly-extending beads 26 and 27 upon the opposite edges of said body or shell. As in Fig. 1, the heads 70 B and C are stretched over the opposite ends of the body and are held in the annular grooves 6 and 7 therein by rings or equivalent devices 8 and 9. On the introduction of air into these tubes 24 and 25 the stretching 75 of the heads over the beads 26 and 27 will take place.

In Fig. 5 the body of the drum is outwardly flared at its opposite ends, as at 28 and 29, respectively, and between these flared portions and located upon the plain surface of the body the rings 30 and 31 are slidable, these rings being peripherally grooved, as at 32, to receive the margins or turned-over portions of the heads B and C, such portions of 85 the head being held in the grooves by rings or equivalent devices 8 and 9.

The inflatable tubes 4 and 5 are located in the spaces bounded by the drum-body, the flared portions 28 and 29 thereof, the turned-over portions of the heads A and B, and the slidable rings 30 and 31. On the introduction of air into these tubes the latter will be inflated outwardly and toward each other, thereby stretching the drumheads radially 95 outward and moving the rings 30 and 31 toward each other for stretching the two heads inward, whereby the tensioning effect is applied in transverse directions.

In Fig. 6 the shell or body of the drum is 100 like that represented in Fig. 5; but instead of fastening the margin of the heads to the body or shell of the drum I wrap the same around the wooden hoops or rings 33 or 34, which encircle the opposite ends of the drum, 105 and a second pair of hoops or rings, as 35 and 36, are adapted to act against the first-mentioned rings, and these hoops 35 and 36 are connected with the drum-body by circular strips of leather or analogous means. The 110 tubes 4 and 5 are introduced into the space between the flared portions 28 and 29 and the leather strips 37 and 38, and the inflation of the tubes will draw the outermost rings 35 and 36 toward each other through the medium 115 of the intermediate strips.

In Fig. 7 the shell or body A is cylindrical and the heads are wrapped around the rings 33 and 34, as shown in the previous figure, the rings being movable toward each other by 120 the second pair of rings 39 and 40, slidably in the cup-shaped receivers 41 and 42, located beyond the ends of the drum and connected to each other and to the shell by means of rods 43. The inflating-tubes are located in 125 the annular receivers 41 and 42 and fit against the rings 39 and 40 for forcing the latter toward each other when said tubes are inflated for the purpose of tightening the heads.

Some of the advantages of the invention 130 are as follows: Simplicity of construction and rapidity and ease of tightening and loosening the heads. The instrument is not bound by the numerous and complex devices usually

present in instruments of this character. The heads can be tightened independently, thereby allowing the use of a very thin snare-head and a heavy batter-head, by means of which a better tone is produced. The heads are tightened absolutely even all around, and consequently there is no danger of drawing the shell or head out of shape in tightening, as is so often done with rope and rod tighteners. The elasticity of the air within the air-tubes allows the heads to expand or contract under atmospheric changes, and thus the heads are preserved. This is a great advantage over the old rod-tighteners, which keep the heads so tight that they lose their elastic properties and fail to vibrate. The drum-shell may be made of very much thinner material, the air-pressure being so even that there is no danger of crushing it. Consequently much lighter instruments can be constructed, which is quite an item to a drummer on a long march. The vibration of the heads is improved, and the shell itself being bound by nothing but a layer of elastic air is free to vibrate. The heads are not as liable to tear on the edge of the shell, as the pull is radially outward instead of down on the shell, and the tighteners never slip, as do the leather braces on the old rope-drums.

Changes in the form, proportion, size, and the minor details of construction within the scope of the appended claims may be resorted to without departing from the spirit or sacrificing any of the advantages of this invention.

Having thus described the invention, what I claim is—

1. A musical instrument including a stretchable head and an expansile head-tensioning tube, substantially as described.
2. A musical instrument including a stretchable head and an endless expansile head-tensioning tube, substantially as described.
3. A musical instrument including a stretchable head, an expansile head-tensioning tube, and means for limiting the movement of the latter, substantially as described.
4. A musical instrument including a body, a stretchable head secured to the body, and an expansile head-tensioning tube located between the head and the body, substantially as described.
5. A musical instrument including a body having a groove, a head on the body, means for securing the head in place, and an expansile head-tensioning device located in said groove, substantially as described.
6. A musical instrument including a body, a head stretched over the same, means for securing the marginal portion of the head to the body, and an expansile head-tensioning device located between the head and the body, substantially as described.

7. A musical instrument including a body, a head stretched over the same, means for securing the head to the body, a tube adapted to receive a fluid and constituting a head-tensioning device, and a supply-pipe communicating with said tube and provided with a detachable cap, substantially as described.

8. A musical instrument including a body, a head stretched over the same, means for securing the head to the body, a tube adapted to receive a fluid and constituting a head-tensioning device, and a supply-pipe communicating with said tube and provided with a detachable cap, and also having a valve, substantially as described.

9. A musical instrument including a body, a head stretched over the same, an expansile tube situated between the head and the body, and a supply-pipe extending through said body and having a removable cap, substantially as described.

10. A musical instrument including a body, a head, a tubular tensioning device, and a split ring surrounding the head and serving to hold the latter in place on the body, substantially as described.

11. A musical instrument including a body having a groove, a head stretched over the body and the edge thereof being disposed in said groove, a ring for holding said edge in said groove, and a tubular tensioning device disposed between the stretched-over portion of the head and the body, substantially as described.

12. A musical instrument having two grooves, a head stretched over the body of the instrument, a split ring for securing the edge of the head in one of the grooves, a tubular tensioning device disposed in the other groove, a ring surrounding the head, and means for connecting the said ring with the body of the instrument, substantially as described.

13. A musical instrument including a body having two grooves, a head stretched over the body, a split ring for securing the head in one of the grooves and having lugs, an adjusting-screw carried by said lugs, a tubular expanding device exposed in the other groove between the head and the body, a supply-pipe communicating with said tube and provided with a detachable cap, a ring surrounding the stretched-over portion of the head, and a rod connecting said last-mentioned ring with said body, substantially as described.

In testimony that I claim the foregoing as my own I have hereto affixed my signature in the presence of two witnesses.

ISAAC HUDSON SAPP.
